UNITED STATES PATENT OFFICE.

WILLIAM C. HUNT, OF TORONTO, ONTARIO, CANADA.

ELECTRIC HEATER AND COOKER.

Application filed February 10, 1928. Serial No. 253,382.

This invention relates to heaters of the type in which a reflector is supported on a stand with the optical axis of the reflector normally laterally directed, but in which the reflector may be tilted so that its optical axis is directed upwardly, an electric heating element being supported from and in front of the reflector. My object is to provide a heater of this type with supporting means 10 on which a kettle or the like may be set while the reflector is positioned with its optical axis laterally directed and which, when the reflector is positioned with its optical axis upwardly directed, may be adjusted to provide a large or small supporting area for cooking utensils, while at the same time the support forms a guard for the heating element.

I attain my object by securing to the reflector adjacent its rim a grid, the surface of the grid lying substantially in the plane of the rim of the reflector and hingedly connecting with said grid wing members which when swung outwardly will extend beyond the rim of the reflector to provide a large horizontal supporting area when the reflector is positioned with its optical axis directed upwardly. I also hingedly connect with said grid a support which is adapted to occupy a substantially horizontal position when the reflector has its optical axis directed laterally, one of the other wings being adapted to be engaged therewith to form a rest for the outer end of the support.

The heater is constructed substantially as hereinafter described and illustrated in the accompanying drawings in which

Fig. 1 is a plan view of the heater with the grid in normal or unextended position, the optical axis of the reflector being vertical;

Fig. 2 is a similar view showing the grid extended;

Fig. 3 is a side elevation, partly broken away, the optical axis of the reflector being laterally directed, and the grid in normal position; and

Fig. 4 is a similar view showing the grid opened up.

In the drawings like numerals of reference indicate corresponding parts in the different figures.

1 is a stand which may be of any suitable design and a head 2 is pivotally secured to its upper end.

The stand is provided with stops 8 and 9, the stop 8 being adapted to limit the movement of the head in one direction and the stop 9 to limit the movement of the head in the other direction. This avoids the necessity of providing a frictional locking engagement between the head and stand, and thus eliminates danger of the head slipping when weight is applied thereon.

Secured to the head is the reflector plate 3, which is of circular concave form, and may by rocking the head on the stand, be positioned so that its optical axis is either vertically or laterally directed.

At the centre of the reflector is mounted a heating element 4, which may be of any ordinary construction and need not, therefore, be described in detail.

Secured to the reflector adjacent the rim is an openwork frame or grid 5, which forms a guard for the heater, and also, when the reflector is arranged with its optical axis directed vertically as shown in Fig. 1, a support on which a cooking utensil may stand. As it is often desirable to heat several utensils at the one time, I hingedly mount on the grid 5 the extension members 6 and 7, which, when swung outwardly as shown in Fig. 2, result in a considerable increase in the total supporting area provided by the grid.

In order that the heater may be used for boiling a kettle or the like when the reflector has its optical axis laterally directed, I secure to the inner face of the grid a platform extension 10, which when the reflector is in the position shown in Fig. 4, lies over the heating element. A portion 11 of the grid is hingedly mounted on the main part, and is adapted, as will be seen from the said Fig. 4, to be swung at an angle to the main part of the grid to form a platform, this platform being provided with projections 12 which engage a cross bar of the extension when said platform is in alignment with the extension. The extension member 7 is also adapted to be swung up and engaged with the platform 11 adjacent its outer end to form a support therefor, and its inner surface, when in said position, may be used as a toast rack.

The platform 11 and member 7 are each provided with handles 13 of fibre or other material less liable to heat up than the metal of which these parts are formed.

The main part of the grid is notched out to

receive the platform 11, and the extension members 6 and 7, so that when the latter are in their folded up position, their outer surfaces are flush with the outer surface of the 5 main part of the grid.

From the above description it will be seen that I have devised a grid which may be used to support cooking utensils whether the optical axis of the reflector is directed 10 laterally or vertically, and which may be opened up to provide a supporting surface having a much larger area than when folded.

What I claim is:

1. In an electric heater, the combination 15 of a stand; a concave reflector mounted on the stand; an electric heating element supported in said reflector; a grid secured adjacent the rim of the reflector and having its outer surface substantially parallel to the 20 plane of the rim; and a platform hingedly mounted on said grid above the element whereby it may occupy a position parallel to the grid or extend outwardly at an angle thereto in the path of the heat reflected by 25 said reflector.

2. In an electric heater, the combination 30 of a stand; a concave reflector mounted on the stand; an electric heating element supported in said reflector; a grid secured adjacent the rim of the reflector and having its outer surface substantially parallel to the plane of the rim; a platform hingedly mounted on said grid above the element whereby it may occupy a position parallel 35 to the grid or extend outwardly at an angle thereto in the path of the heat reflected by said reflector; and means for supporting the platform in said extended position.

3. In an electric heater, the combination 40 of a stand; a concave reflector mounted on the stand; an electric heating element supported in said reflector; a grid secured adjacent the rim of the reflector and having its outer surface substantially parallel to the 45 plane of the rim; a platform hingedly mounted on said grid whereby it may occupy a position parallel to the grid or extend outwardly at an angle thereto; and a fixed extension of said platform on the inner side 50 of the grid.

4. In an electric heater, the combination of 55 a stand; a concave reflector mounted on the stand; an electric heating element supported in said reflector; a grid secured adjacent the rim of the reflector and having its outer surface substantially parallel to the plane of the rim; a platform hingedly mounted on said grid whereby it may occupy a position parallel to the grid or extend outwardly 60 at an angle thereto; and a supporting member hingedly mounted on said grid whereby it may occupy a position parallel to the grid or engage with the platform adjacent the outer end thereof when the latter is in extended position.

5. In an electric heater, the combination 70 of a stand; a concave reflector mounted on the stand; an electric heating element supported in said reflector; a grid secured adjacent the rim of the reflector and having its outer surface substantially parallel to the plane of the rim; a platform hingedly mounted on said grid whereby it may occupy a position parallel to the grid or extend outwardly at an angle thereto; a supporting 75 member hingedly mounted on said grid whereby it may occupy a position parallel to the grid or engage with the platform adjacent the outer end thereof when the latter is in extended position; and a fixed extension 80 of said platform on the inner side of the grid.

6. In an electric heater, the combination 85 of a stand; a concave reflector mounted on the stand; an electric heating element supported in said reflector; a grid secured adjacent the rim of the reflector and having its outer surface substantially parallel to the plane of the rim; a platform hingedly mounted on said grid whereby it may occupy 90 a position parallel to the grid or extend outwardly at an angle thereto; and a fixed extension of said platform on the inner side of the grid, said grid being recessed to receive the platform and supporting member 95 whereby when they are in folded position their outer surfaces are substantially flush with the outer surface of the grid.

7. In an electric heater, the combination of 100 a stand; a concave reflector mounted on said stand; an electric heating element supported therein; a grid secured adjacent the outer rim of said reflector and having its outer surface substantially parallel to the plane of 105 said rim; and wing extensions hingedly connected with said grid whereby they may occupy a position over the grid or extend outwardly therefrom in alinement with its outer surface.

8. In an electric heater, the combination 110 of a stand; a concave reflector mounted on said stand; an electric heating element supported thereon; a grid secured adjacent the outer rim of said reflector and having its outer surface substantially parallel to the 115 plane of said rim; wing extensions hingedly connected with said grid whereby they may occupy a position over the grid or extend outwardly therefrom, in alinement with its outer surface; and a platform hingedly 120 mounted on said grid whereby it may occupy a position parallel to the grid or extend outwardly at an angle thereto.

9. In an electric heater, the combination of 125 a stand; a concave reflector mounted on said stand; an electric heating element supported thereon; a grid secured adjacent the outer rim of said reflector and having its outer surface substantially parallel to the plane of said rim; wing extensions hingedly 130

connected with said grid whereby they may occupy a position over the grid or extend outwardly therefrom in alignment with its outer surface; and a platform hingedly mounted on said grid whereby it may occupy a position parallel to the grid or extend outwardly at an angle thereto, one of said extensions being adapted to be engaged with the platform adjacent its outer end to support the latter when in extended position. ¹⁰
